BASKETBALL BACKSTOP

Michael Hornung and Victor W. Claussen,
Spearville, Kans.

Application December 26, 1956, Serial No. 44,331

Term of patent 14 years

(Cl. D34—5)

Fig. 1 is a side elevation of a basketball backstop showing our new design;

Fig. 2 is a front elevation of same; and

Fig. 3 is a top plan view of same.

We claim:

The ornamental design for a basketball backstop, substantially as shown.
